(74) Attorney, Agent, or Firm—Fross Zelnick Lehrman & Zissu, P.C.; David I. Greenbaum; Lawrence E. Apolzon

(57) **CLAIM**

The ornamental design for a crown for wristwatch, as shown and described.

DESCRIPTION

FIG. 1 is a perspective view of a crown for wristwatch showing the new design;

FIG. 2 is a top view of the crown shown in FIG. 1; and, FIG. 3 is a right side view of the crown shown in FIG. 1. The broken line showing of a watch case, watch face, watch hands, watch band and screws is for illustrative purposes only and forms no part of the claimed design.

UNITED STATES PATENT AND TRADEMARK OFFICE
CERTIFICATE OF CORRECTION

PATENT NO. : Des. 491,827 S
DATED : June 22, 2004
INVENTOR(S) : Eric Bonnet

Page 1 of 5

It is certified that error appears in the above-identified patent and that said Letters Patent is hereby corrected as shown below:

The Title page showing an illustration figure, should be deleted and substitute therefore the attached page.

Delete drawings sheets 1-3 and substitute therefore the drawings sheets consisting of sheets 1-3 as shown on the attached page

Signed and Sealed this

Fifteenth Day of March, 2005

A handwritten signature in black ink, appearing to read "Jon W. Dudas". The signature is written in a cursive style with a large, stylized "J" at the beginning.

JON W. DUDAS
Director of the United States Patent and Trademark Office
